Application November 13, 1937, Serial No. 174,275
In Germany December 7, 1936

9 Claims. (Cl. 179—86)

A prior application of Benedikt Kudrna, Ser. No. 104,374, filed October 7, 1936, concerns a circuit arrangement for selective calling by means of condenser-resistance arrangements which are influenced by impulses of different durations at the branch stations of party lines in remote communication systems and more particularly telephone systems, in which after the transmission of a selective impulse by means of which in addition to the condensers at the wanted branch station also condensers at branch stations (having ringing periods of shorter duration) which are not wanted, are brought to a state of charge (completely charged or completely discharged) which enables the associated connecting relay to be controlled, these condensers at the stations which are not wanted are rendered inoperative by being converted to a state of charge (partially or wholly discharged or charged respectively) which no longer enables the associated connecting relays to be controlled.

According to the prior application the condensers at the stations which are not wanted are brought into a condition which no longer enables the associated connecting relays to be controlled, from the sending station.

The present patent of addition is concerned with an improvement on this arrangement and consists in that the conversion of the condensers at the branch stations which are not wanted to a state of charge which no longer enables the associated connecting relays to be controlled is effective by discharge paths disposed at each branch station.

The use of discharge paths at each branch station produces the special advantage that after the transmission of the selective impulse no further discharge impulses need be transmitted from the sending station.

This has the further advantage that account of the omission of discharge current impulses transmitted after the selection the selecting time is reduced.

The rendering inoperative of the excess charge of the condensers over the discharge paths at each of the branch stations which are not wanted is conveniently effected in that when the discharge path becomes effective relays are influenced which either convert the associated condensers to a state of charge which no longer enables the connecting relays to be controlled or disconnected, or disconnect the connecting relays for a period of time lasting until the associated condensers are brought to a state of charge which no longer enables the connecting relays to be

controlled. For the purpose of increasing efficiency both measures can be employed simultaneously.

The invention will be explained in detail with reference to the drawing but is not to be considered as limited to this. Only those circuit details which are necessary for understanding the invention and differ from the arrangements shown in the prior application are represented in the drawing.

As may be seen from the drawing a plurality of branch stations AST are connected to the party line GL leading to the central station ZSt. The branch stations are adapted to be called selectively from the central station ZSt. The individual branch stations in the present case are selected only by means of direct current impulses of varying duration. By using polarized receiving relays, however, direct current impulses of different durations and directions can be employed.

At each branch station associated with the station ZSt is an impulse receiving relay J and a condenser-resistance arrangement C, Wi, a discharge path E, an auxiliary relay B, a connecting relay A and a source of direct current. The individual branch stations only differ from one another as regards the properties of the condenser resistance arrangements Wi which determine the charging period of the condenser C associated therewith. The magnitude of the resistances corresponds to the various selecting periods. The discharge paths, for example glow lamps, are all operative on the attainment of the same potential by the condensers with which they are associated.

When a direct current of a particular duration is transmitted from the central station ZSt in the known way the relays J at all the branch stations energize and connect the corresponding condensers C to the resistances Wi.

It will be considered for example that a direct current impulse is transmitted for selecting the branch station AST1. The duration of this impulse must on the one hand be sufficient to bring the condenser C1, over to resistance W1, into a condition enabling the connecting relay A1 to be controlled but on the other hand must not be of as great duration as the charging period necessary for rendering the discharge path operative.

The impulse serving to select the branch station AST1 will not succeed in influencing the connecting relays in the branch stations having a longer selecting period. At the branch stations having a shorter selecting period, for example

AST2, on the other hand the associated discharge path becomes operative when the charging period necessary for controlling the connecting relays is over-stepped and brings about the discharge of the associated condensers and/or the disconnection of the connecting relays.

The switching operations in detail are as follows:

- At the branch station AST1 the condenser C1 is charged over contact 1_{j1} and resistance W1 after relay J1 has operated. Since in the case in question the duration of the direct current impulse transmitted corresponds to the selecting period of the branch station AST1 the condenser 15 C1 is brought to a state of charge which enables the connecting relay A1 to be controlled, without the discharge path disposed in parallel to the condenser C1 becoming operative. On the release of relay J1 the condenser discharge over the 20 contact 1_{j1} when restored to its normal position exerts its full effect on the connecting relay A1. Relay A1 at contact 5a1 and 6a1 causes the wanted subscriber's station TSt1 to be connected to the party line GL.
- 25 The release of the connection takes place when the subscriber at station TSt1 hangs up his receiver. The restoration of the connecting relay A1 can be controlled, for example, by momentarily opening contacts (not shown) in the locking circuit of relay A1 when the receiver is replaced upon the switchhook, or in any other well known manner.

At the branch station AST2 the excess charge on the condenser C2 must be rendered inoperative so that the connecting relay A2 does not operate in the present case (the impulse transmitted being longer than the selecting period of the branch station AST2).

This is arranged for in that on the further 40 charging of the condenser C2 over the operated contact 7_{j2} of relay J2 and resistance W2, the discharge path E2 disposed in parallel with the condenser C2 becomes operative. Consequently the relay B2 in series with the discharge path 45 E2 operates, short circuits the discharge path E2 at contact 8b2 and at contact 9b2 disconnects the connecting relay A2. Relay B2 locks up in parallel with the condenser C2 for the rest of the duration of the selecting impulse and further 50 until after the termination of the selecting impulse by the discharge of condenser C2. No discharge of the condenser C2 over the connecting relay A2 can take place so long as relay B2 is operated. The release of relay B2 can further 55 be delayed by copper damping.

In this way the condenser C2 is brought to a state of charge which no longer enables the connecting relay A2 to be controlled and at the same time the connecting relay A2 is disconnected until the state of charge necessary for controlling the connecting relay A2 no longer obtains. The connecting relay A2 thus does not energize on the termination of the selecting impulse and the restoration of the contact 7_{j2} at branch station AST2 which is not wanted, so that a false connection over contacts 11a2 and 12a2 is prevented.

What is claimed is:

1. In a telephone system, a party line, a plurality of stations on said line, a condenser for each station, means at each station operated responsive to a pulse of current received over said line for charging said condensers, means at each station for connecting with said line, each of 75 said last means operated only if its associated

station condenser has been charged for a predetermined duration, and means at each station effective only responsive to an overcharge of the associated station condenser for preventing the connecting means thereat from being operated.

2. In a telephone system, a party line, a plurality of stations on said line normally prevented from connecting with the line; a condenser, a connecting relay, and a disconnecting relay associated with each of said stations; means at each of said stations operated responsive to the transmission of a station selecting pulse of current over said line, the pulse operated means at the wanted station controlling its associated condenser and connecting relay to thereby connect the station with the party line, and the pulse operated means at all other said stations controlling their associated condenser and disconnect relay to thereby prevent connection of all of said other stations to said party line.

3. In a telephone system, a party line, two stations normally disconnected from said line, a condenser and a connecting relay individual to each of said stations, means at each station operated by a station selecting pulse transmitted over said line for charging its associated station condenser, the duration of charging time being sufficient to completely charge one of said condensers and to overcharge the other of said condensers, means at each of said stations effective only responsive to an overcharge of the condenser thereat for disconnecting the associated connecting relay to prevent its operation and for discharging the overcharged condenser, and contacts controlled by said pulse operated means for completing a discharge circuit for said completely charged condenser through its connecting relay to thereby operate the same and connect the associated station to said party line.

4. In a telephone system, a line over which a pulse of current is transmitted, a station normally disconnected from said line, a first relay individual to said station operated responsive to said current pulse, a condenser and a connecting relay for said station, means controlled by the operation of said first relay for charging said condenser and for discharging the same through said connecting relay when said first relay restores, said connecting relay non-responsive to discharge currents of insufficient strength and operated responsive to discharge currents of proper strength to connect the station to said line, and means responsive only when said current pulse is more than sufficient to completely charge said condenser for disconnecting said connecting relay from said discharge currents.

5. In a telephone system, a party line, a plurality of stations on said line normally disconnected therefrom, a pulse receiving relay bridging the conductors of said line at each of said stations, said relays operated responsive to the transmission of a current pulse over said line, a condenser and charging circuit therefor at each station completed by the operation of its associated pulse receiving relay, a discharge circuit for each condenser completed responsive to the restoration of its associated pulse receiving relay, and connecting means at each station operated responsive to the discharge of the associated condenser for connecting its station to said line, the strength of the discharge current through said connecting means determining the station to be connected to said party line.

6. In a telephone system, a party line, two sta-

tions on said line, means at each station operated responsive to a pulse of current received over said line, a condenser and charging circuit therefor completed by the operation of said last means, 5 a discharge circuit for said condenser and a connecting relay included therein for connecting the station to the line, said pulse receiving means controlling the discharge circuit of said condensers, a disconnect relay at each station operative to prevent the operation of its associated connecting relay, and a space discharge device for each station effective only responsive to an overcharge of its associated condenser to control the operation of its associated disconnect relay.

7. In a system as claimed in claim 6, in which the operation of said disconnect relay short-circuits said space discharge device to render it ineffective.

8. In a system as claimed in claim 6, in which 5 the operation of the disconnect relay completes a circuit for discharging the associated station condenser.

9. In a system as claimed in claim 6, in which the disconnect relay upon operation completes 10 a locking circuit for itself including the charging circuit for the associated condenser.

FRITZ LUBBERGER.
